RADIOACTIVE CONTAINER

Donald McHardy Ferguson, Marblehead, Mass., assignor to the United States of America as represented by the Secretary of the Air Force

Application August 29, 1956, Serial No. 606,935

8 Claims. (Cl. 250—106)

(Granted under Title 35, U. S. Code (1952), sec. 266)

The invention described herein may be manufactured and used by or for the United States Government for governmental purposes without payment to me of any royalty thereon.

This invention relates to a container for radioactive material and, more particularly, to a container having a radioactive source therein that is exposed to other materials without radiation from the container.

In the use of radioactive materials, there exists the danger of radiation to the area in which the materials are disposed as well as to any persons in the area. Devices have been employed to transport radioactive materials from one area to another without danger of radiation to anyone. However, there still exists the problem of exposing other materials to the radioactive source without hazard to the area in which the materials are exposed to the radioactive source and to the persons in the area.

Accordingly, an object of this invention is to provide a container for radioactive sources that permits a material to be exposed to a radioactive source without radioactive contamination of the area in which the container is located or the persons therein.

Another object of this invention is to provide a container for radioactive sources that may be used in an enclosed area without any complex safety precautions.

Other objects of this invention will be readily perceived from the following description.

This invention relates to a container for radioactive material comprising a housing of radiation shielding material having two cavities therein with the cavities being in communication with each other. One of the cavities has a radioactive source therein. Suitable means are disposed in the end of this cavity to prevent radiation from the radioactive source to the exterior of the housing. The other cavity has a rotatable member disposed therein. This rotatable member has a recess that registers with the radioactive source for exposure thereto without any radiation to the exterior of the housing.

The attached drawing illustrates a preferred embodiment of the invention, in which:

Fig. 1 is a top plan view of the container of the present invention; and

Fig. 2 is a vertical sectional view taken along the line 2—2 of Fig. 1.

Referring to the drawing, there is shown a container for radioactive material comprising a housing 10 having a wall 11 and top 11a preferably of stainless steel while the interior 12 of the housing 10 is filled with lead or other suitable radiation shielding material. The thickness of the lead depends on the intensity of radiation so that the physical dimensions of the container 10 will be varied in accordance with the maximum intensity of radiation expected from the radioactive source to be used with the container.

The housing 10 has a cavity 14 extending from the top

11a thereof to the interior of the housing (see Fig. 2). The housing 10 has a second cavity 15 extending from the exterior of the housing into the interior thereof at substantially right angles to the first cavity 14. The inner ends of the cavities 14 and 15 are in communication with each other (see Fig. 2).

5 A holder 16 having a radioactive source 17 in the interior thereof is designed for insertion within the first cavity 14. The holder 16 is secured to the top 11a of the housing 10 by insertion of pins 18, which are on the top 11a of the housing 10, in bayonet slots 19 in end walls 20 of the holder 16. Thus, by inserting the pins 18 within the large portion of each of the bayonet slots 19 and then turning the holder 16 slightly, the enlarged head of the pin 18 fits within the smaller portion of the bayonet slot 19 to lock the holder 16 to the housing 10.

10 A plug 21, which is formed of a radiation shielding material such as lead, is disposed within the upper portion of the first cavity in the interior of the holder 16, which 20 is annular in cross section. The plug 21 is supported within the holder 16 by a flange 22. Thus, from Fig. 2, it will be observed that the plug 21 prevents any radiation from the radioactive source 17 to the exterior of the housing 10 through the first cavity 14.

15 The housing 10 has a base 23 preferably of stainless steel from which a shaft 24 extends upwardly on an axis parallel to the axis of the first cavity 14. A cylindrical member 25 such as a tray is mounted on the shaft 24 for rotation thereabout. The tray 25 has its walls 26 formed 30 preferably of stainless steel while the interior 27 thereof is filled with a radiation shielding material, preferably lead. The tray 25 has a recess 28 in one portion of the periphery thereof whereby rotation of the member 25 about the axis of the shaft 24 moves the recess 28 into alignment with the first cavity 14. When the recess 28 is in alignment with the first cavity 14, it will be readily observed that any object in the recess 28 is exposed to the radioactive source 17 since the cavities 14 and 15 are in communication with each other. However, the structure of the remainder of the member 25 being of a radiation shielding material within the interior 27 thereof prevents radiation through the second cavity 15 to the exterior of the housing 10. It will be noted from Fig. 2

35 that the top wall of the second cavity 15 has a portion 29 that serves as an abutment for the lowermost portion of the holder 16 to insure that the radioactive source 17 is sufficiently above the dividing line between the tray 25 and the top wall of the second cavity 15 to cause the radiation 40 to have to follow a zigzag path and thereby prevent radiation from the interior of the housing 10.

45 A bearing 30 between the shaft 24 and the lower surface of the member 25 accommodates the thrust loading produced by the weight of the tray 25. An upper bearing 50 31 between the shaft 24 and the tray 25 reduces friction of the shaft 24 due to the eccentric loading of the rotatable member 25 that is produced by the objects disposed within the recess 28. A semicircular member 32 is secured to the housing 10 to serve as a guard against

55 physical damage to the rotating tray 25. This guard member 32, which is preferably stainless steel, also is an added protection against radiation. A plurality of members 33 (three shown in Fig. 1) are secured to the exterior wall of the housing 10 to provide a means for transporting the container, which is very heavy because of the mass of lead embodied within the interior of the housing 10. The plug 21 may be easily removed from the interior of the holder 16 by a handle 34.

60 Considering the operation of the present invention, it will be seen that the tray 25 is rotated by a handle 35 on the tray from a position in which the recess 28 is outside of the housing 10 to a position in which the recess 28 is

disposed in alignment with the first cavity 14. When the recess 28 is outside of the housing 10, the object or objects to be exposed to the radioactive source 17 are placed within the recess; the tray 25 is then rotated by the handle 35 to the position in which the recess 28 is in alignment with the first cavity 14. The handle 35 is located on the tray 25 so that the handle abuts against the wall of the housing 10 when the recess 28 is in alignment with the first cavity 14 (see Fig. 1). As previously explained, the radiation shielding material of the plug 21 prevents any radiation through the first cavity 14 to the exterior of the housing 10 while the radiation shielding material of the rotating tray or member 25 prevents any radiation through the second cavity 15 to the exterior of the housing 10. The interior 12 of the housing 10, as previously explained, is formed of radiation shielding material so that no radiation occurs from the radioactive source 17 through the housing 10.

An advantage of this invention is that various materials may be exposed to a radioactive source without any hazard to the operator of the container in which the radioactive source is disposed.

For purposes of exemplification, a particular embodiment of the invention has been shown and described according to the best present understanding thereof. However, it will be apparent that changes and modifications in the arrangement and construction of the parts thereof may be resorted to without departing from the true spirit and scope of the invention.

I claim:

1. A container for radioactive material including a housing of radiation shielding material, said housing having two cavities in communication with each other, a radioactive source disposed in one of the cavities, means composed of radiation shielding material disposed in said one cavity to prevent radiation from said radioactive source to the exterior of said housing, and a rotatable member disposed in the other of the cavities, said rotatable member having a recess therein, the recess of the rotatable member registering with the radioactive source in said one cavity for exposure thereto.

2. A container for radioactive material including a housing of radiation shielding material, said housing having two cavities in communication with each other substantially at right angles, a radioactive source disposed in one of the cavities, means composed of radiation shielding material disposed in said one cavity to prevent radiation from said radioactive source to the exterior of said housing, and a rotatable member disposed in the other of the cavities, said rotatable member having a recess therein, the recess of the rotatable member registering with the radioactive source in said one cavity for exposure thereto.

3. A container for radioactive material comprising a housing of radiation shielding material, said housing having a first cavity and a second cavity therein, the inner ends of said first and second cavities communicating, a radioactive source disposed within the first cavity, radiation shielding means preventing radiation through the first cavity to the exterior of the housing, and a member of radiation shielding material including a recess therein disposed in the second cavity, said member being rotatable whereby an object disposed in the recess is exposed to the radioactive source without any radiation through the second cavity to the exterior of the housing.

4. A container for radioactive material comprising a housing of radiation shielding material, said housing having a first cavity and a second cavity therein, the inner ends of said first and second cavities communicating, a radioactive source disposed within the first cavity, radiation shielding means disposed in the first cavity preventing radiation through the first cavity to the exterior of the housing, and a member of radiation shielding material including a recess therein disposed in the second cavity, said

member being rotatable whereby an object disposed in the recess is exposed to the radioactive source without any radiation through the second cavity to the exterior of the housing.

5. A container for radioactive material comprising a housing of radiation shielding material, said housing having a first cavity and a second cavity therein, the inner ends of said first and second cavities communicating, a radioactive source disposed within the first cavity, radiation shielding means preventing radiation through the first cavity to the exterior of the housing, a shaft extending transverse to the second cavity, and a member of radiation shielding material mounted on said shaft for rotation thereon, said member having a recess therein movable from a position outside of said housing to a position in which an object in the recess is exposed to the radioactive source without any radiation through the second cavity to the exterior of the housing.

6. A container for radioactive material comprising a housing of radiation shielding material, said housing having a first cavity and a second cavity therein, the inner ends of said first and second cavities communicating, a radioactive source disposed within the first cavity, radiation shielding means preventing radiation through the first cavity to the exterior of the housing, a shaft extending transverse to the second cavity, a member of radiation shielding material mounted on said shaft for rotation thereon, said member having a recess therein movable from a position outside of said housing to a position in which an object in the recess is exposed to the radioactive source without any radiation through the second cavity to the exterior of the housing, and a guard member surrounding the periphery of the member mounted on the shaft to protect the member mounted on the shaft and aid in preventing radiation.

7. A container for radioactive material comprising a housing of radiation shielding material, said housing having a first cavity extending from the exterior thereof to the interior of the housing, said housing having a second cavity extending from the exterior thereof to the interior of the housing, the interior ends of the first and second cavities being in communication with each other, a holder having a radioactive source therein being disposed in the first cavity, a plug of radiation shielding material disposed within the holder to prevent radiation from the radioactive source to the exterior of the housing through the first cavity, and a member of radiation shielding material rotatably mounted in the second cavity, said member having a recess therein movable into the portion of the second cavity in communication with the first cavity whereby an object in the recess is exposed to the radioactive source without any radiation to the exterior of the housing through the second cavity.

8. A container for radioactive material comprising a housing of radiation shielding material, said housing having a first cavity extending from the exterior thereof to the interior of the housing, said housing having a second cavity extending from the exterior thereof to the interior of the housing at substantially right angles to the first cavity, the interior ends of the first and second cavities being in communication with each other, a holder having a radioactive source therein being disposed in the first cavity, a plug of radiation shielding material disposed within the holder to prevent radiation from the radioactive source to the exterior of the housing through the first cavity, and a member of radiation shielding material rotatably mounted in the second cavity, said member having a recess therein movable into the portion of the second cavity in communication with the first cavity whereby an object in the recess is exposed to the radioactive source without any radiation to the exterior of the housing through the second cavity.
